Inventor:
L.J. Gottschalk

UNITED STATES PATENT OFFICE

91,236

DESIGN FOR A REFRIGERATOR CABINET

Lionel J. Gottschalk, New Orleans, La.

Application May 5, 1933. Serial No. 48,024

Term of patent 7 years

To all whom it may concern:

Be it known that I, LIONEL J. GOTTSCHALK, a citizen of the United States, residing at 914 Union Street, New Orleans, in the parish of Orleans and State of Louisiana, have invented a new, original, and ornamental Design for a Refrigerator Cabinet, of which the following is a specification, reference being had to the accompanying drawing, forming part thereof.

The figure is a perspective view of a refrigerator cabinet, embodying my new design.

I claim:

The ornamental design for a refrigerator cabinet, as shown.

LIONEL J. GOTTSCHALK.
